UNITED STATES PATENT OFFICE.

CHARLES DORFFEL, OF CHICAGO, ILLINOIS, ASSIGNOR OF ONE-HALF TO
HERMAN HOLZNAGEL, OF SAME PLACE.

DESIGN FOR A HOLDING-PLATE FOR INDICATORS.

SPECIFICATION forming part of Design No. 33,868, dated January 8, 1901.

Application filed December 8, 1900. Serial No. 39,232. Term of patent 14 years.

To all whom it may concern:

Be it known that I, CHARLES DORFFEL, a citizen of the United States, residing at Chicago, in the county of Cook and State of Illinois, have invented and produced a new and original Design for Holding-Plates for Indicators; and I do hereby declare the following to be a full, clear, and exact description of the same, reference being had to the accompanying drawings, forming a part thereof.

This invention relates to a new and original design for a holding-plate for office-indicators, and is illustrated in the accompanying drawings.

15 In the drawings, Figure 1 is a front elevation of a holding-plate for office-indicators, showing my design. Fig. 2 is a longitudinal sectional elevation.

As shown in the drawings, the design comprises a substantially flat rectangular plate A of slight thickness having a surrounding marginal bead or edge a and having at each of the corners thereof a hole B. Surrounding each of the holes B and concentric therewith is a circular bead to add to the ornamentation of the plate. Within the marginal bead and spaced therefrom is a bead parallel with

the sides or edges of the plate, as indicated at D.

E E indicate two slots, one near each end of bead D and parallel therewith for the greater part of their length, said slots having at the upper ends laterally-extending portions e terminating at the beads D. As shown in the drawings, the upper ends of the edges of the slots are rounded off, as indicated.

The essential feature of the design is a plate of substantially rectangular shape having the oppositely-arranged parallel slots, each having at its upper end a laterally-extending portion.

Having thus described my invention, what I claim, and desire to secure by Letters Patent, is—

The design for a holding-plate for office-indicators, substantially as herein shown and described.

In testimony whereof I affix my signature in presence of two witnesses.

CHARLES DORFFEL
